UNITED STATES PATENT OFFICE.

HELGE GUSTAF TORULF, OF STOCKHOLM, SWEDEN.

MEANS FOR SINTERING FINE ORES OR PULVEROUS ORES.

Application filed October 30, 1924, Serial No. 746,848, and in Sweden August 22, 1923.

The present invention relates to means for sintering fine ores.

The object of the invention is to provide an apparatus in which a plurality of independently movable sintering pans are used in which the sintering of the ore is performed by the combustion of fuel mixed with the ore by means of a down draft generated by exhausters while maintaining the pans stationary during the performance of the sintering operation, and further to provide means whereby the loading of the pans and the removal of the pans with the sintered material to a distant discharge place can be effected systematically in such manner that a practically continuous operation is secured.

The invention consists, chiefly in a sintering system, comprising independent portable sintering vessels, exhausting apparatus, a plurality of work positions communicating with said exhausting apparatus and each adapted to receive a sintering vessel, a railway extending from the work positions to a distant discharge place for the sintered material, a charge preparing apparatus, a movable charge filling device, and a second railway supporting said charge filling device and extending between the charge preparing apparatus and the work positions.

In the accompanying drawings, Figure 1 is a diagrammatic elevation of a plant for sintering ores according to this invention, Fig. 2 is a diagrammatic top plan view of said plant, and Fig. 3 is a diagrammatic cross section thereof. Figs. 4, 5 and 6 are corresponding views of a modified plant.

With reference to Figs. 1-3, the numeral 1 designates a charge preparing house to which the materials to be sintered are carried by means of a railway 2 or the like. Provided within the charging house are, preferably, a mingler 3 for preparing the mixture comprising fuel and fine ores which is to be filled into the sintering vessels, a hopper 4 (Fig. 2) adapted to receive the material from the railway 2 and supply it to the mingler, and an elevator 41 or the like to lift the material from the mingler and supply it to another hopper 5 (Fig. 1). The charge preparing house is situated at one end of a platform 6 comprising a series or row of work positions which extends along one side of an exhausting house 7. Leading from exhausters 9 within the house 7 to each of the work positions on the platform 6 is a suction pipe 8. While two exhausters

are shown in Fig. 2, it is to be noted that the number of the exhausters may be chosen to answer to the requirements so that even every vessel may have its individual exhaust 60 or section of an exhaust. Each work position is adapted to support a portable sintering vessel 10, preferably in the shape of a tilttable receptacle having supporting arms of any appropriate type. 65

Provided at about the level of the upper edge of the sintering vessels when standing on the platform is a railway 11 extending over the platform and at a still higher level, a second railway 12 is provided. The railway 11 carries a movable charge filling receptacle 13 as well as a movable igniter 14. The charge filling receptacle 13 is open topped and shaped as a funnel at its lower end and provided with any suitable type of removable bottom. The railway 12 carries a crane 15 with means for lifting and supporting a sintering vessel. The platform 6 with a corresponding part of the railway 12 is enclosed within a house 16. The railway 12 extends to an emptying place 17 (Fig. 1), where there is a receiving device comprising a chute 18 having a sieve (not shown) in the bottom and a hopper 19 below said sieve. The hopper 19 is situated above a railway 20, and the chute 18 ends above another railway 21. Standing on the railways 20 and 21 are wagons 22 and 23, respectively. 75 80 85

The plant described operates as follows: 90 As soon as the sintering of the material contained in any vessel on the platform 6 is completed, said vessel is lifted by means of the crane 15 and carried up to the emptying place where it is emptied. The sintered material now slides through the chute 18 down into the wagon 23, whereas any material not sintered, should there be such material, will pass the sieve to a large extent and drop down into the wagon 22. The emptied vessel is then restored by the crane 100 15 and put on its place on the platform. While the emptying is taking place the charge filling receptacle 13 is carried up below the hopper 5 and filled with material to be sintered and immediately after the vessel is put down on its place again, the receptacle 13 is carried up above the vessel and the bottom thereof opened so that the vessel will be filled with material. The fresh material thus supplied is then ignited 105 110 by means of the igniter 14 to initiate the sintering operation. The crane 15, having

restored a vessel to its place, is immediately ready to take a new vessel, and as soon as the filling of a vessel is completed the charge filling receptacle 13 may again receive a 5 fresh charge so as to be ready to fill the next vessel emptied. The operation may thus continue without interruption.

The elevated railway 12 may be replaced by a railway at one side of the platform 6, 10 and on this railway a separate wagon may be used having a platform into which a vessel with its sintered contents may be displaced laterally from the platform 6, in which case the vessels may, preferably, be 15 provided with wheels.

With reference to Figs. 4-6 it is to be noted that the plant shown therein corresponds to that described as regards the ex- 20 hauster house 7 and its design, the platform 6 with its work positions, the charge preparing house 1, and the railway 11 with the movable charge filling receptacle 13 and the movable igniter 14. The plant shown in 25 Figs. 4-6 further comprises a longitudinally movable travelling crane 30 with its wagon 31 having means for lifting and carrying a sintering vessel 10. The house 16 also contains a railway 32 extending to an emptying place 17, which supports a wagon 33 adapted 30 to carry a sintering vessel.

Said plant operates as follows: A vessel 35 the contents of which is completely sintered is removed from its work position by means of the wagon 31 and placed upon the wagon 33 which thereupon carries the vessel up to the emptying place 17 where the vessel is emptied. The vessel emptied is carried by the wagon 33 back into the house 16, lifted 40 by means of the wagon 31 and again placed on its position on the platform 6. The charge filling receptacle 13 filled in the meantime is then carried up above the ves-

sel and supplies a fresh charge thereto which will then be ignited by means of the igniter 14.

What I claim is:

1. A sintering system, comprising independent portable sintering vessels, exhausting apparatus, a plurality of work positions each adapted to receive a sintering vessel, an individual suction pipe connecting each work position with said exhausting apparatus, a railway extending from the work positions to a distant discharge place for the sintered material, and means movable on said railway and adapted to transport the vessels with the sintered material from the work positions to the discharge place, a charge preparing apparatus, a second railway extending between said discharge preparing apparatus and the work positions, and a charge filling apparatus movable on the last mentioned railway.

2. A sintering system, comprising independent portable sintering vessels, exhausting apparatus, a plurality of work positions each adapted to receive a sintering vessel, an individual suction pipe connecting each work position with said exhausting apparatus, a railway extending from the work positions to a distant discharge place for the sintered material, a movable crane on said railway adapted to lift and transport the vessels with the sintered material from the work positions to the discharge place, a second railway extending along the work positions, and a charge filling apparatus and an igniting apparatus both movable on the last-mentioned railway to all of the work positions.

In testimony whereof I have signed my name.

HELGE GUSTAF TORULF.
